SCINTILLATING SIGN

Wallace G. McIlvanie, Yakima, Wash.

Application May 7, 1938, Serial No. 206,668

5 Claims. (Cl. 40—139)

This invention relates to a scintillating sign.

An object of the invention is the provision of a sign formed of words or figures with either the word or the figure being made of sections of reflecting surfaces upon which light rays are projected with either the reflecting surfaces being agitated or the light rays being moved in such a manner that the same effect would be produced from the reflecting surfaces.

10 Another object of the invention is the provision of a sign containing letters for advertisements or figures of various kinds may be employed either singly or in connection with words, the letters or figures being formed of a plurality of reflecting surfaces which may be oscillated uniformly or in an irregular manner so that when light rays are projected onto the reflecting surfaces an observer will get the effect of a scintillating or sparkling sign.

20 A further object of the invention is the provision of a sign in which the display elements are formed of a plurality of rockable mirrors upon which light rays are directed so that a scintillating effect of the projected light will be had.

25 This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

35 Figure 1 is a view in elevation partly in section of a sign constructed in accordance with the principles of my invention.

Figure 2 is a bottom plan view of the device with the base of the housing removed.

40 Figure 3 is a transverse vertical section taken along the line 3—3 of Figure 1.

Figure 4 is an enlarged fragmentary view in elevation showing part of the operating mechanism for oscillating the mirrors of the sign,

45 Figure 5 is a vertical section of one of the mirrors forming the sign showing the irregular rear surface.

Figure 6 is a front view in elevation of the reflecting surface disclosed in Fig. 5.

50 Figures 7 and 8 show, respectively, modified forms of the rear surfaces of the reflecting members.

Figure 9 is a view in perspective of a modified form of the invention.

55 Referring more particularly to the drawings, 10

designates generally a housing in which the operating mechanism for oscillating reflecting surfaces is contained. A cover 11 is secured in any approved manner to the top of the housing to protect the mechanism against the elements. 5 The bottom 12 of the housing provides a support for the sign for any suitable position of said sign. The housing may be made of any shape and the shape will depend upon the particular conditions met with where variations in the design will 10 require changes.

An electric motor 13 is located within the housing 10 and is supported by the floor 12 and is secured in any suitable manner to said base member. A pulley 14 is connected to a drive shaft 15 15 of the motor and this pulley by means of a belt 16 drives a second pulley 17 secured to a shaft 18 which is mounted in bearings 19 supported from the top 11 of the housing 10.

A pitman 20 has one end pivotally mounted on 20 an eccentric pin 21 secured to the side face of the pulley 17. The opposite end of the pitman is pivotally connected at 22 with a rockable lever 23 rigidly connected with a rod 24 at its central point.

A pair of reciprocating links 25 and 26 are located within the housing 10. Link 25 is pivotally connected at 27 with one end of the lever 23 while the adjacent end of the link 26 is pivotally connected at 28 with the opposite end of said 30 lever.

A plurality of levers 30 have their outer ends pivotally connected at 31 with the link 25. A plurality of alternately disposed levers 32 have their outer ends pivotally connected at 33 to the link 26. The last-mentioned series of levers extends 35 diametrically opposite to the levers 30 and are alternately disposed with respect to the levers 30.

A plurality of rods, designated by the numerals 35 to 40, inclusive, are vertically mounted and have their lower ends rigidly connected with the inner ends of the adjacently disposed levers 30. A plurality of rods 41 to 45, inclusive, are alternately disposed with respect to the rods 35 and 40, inclusive, and are respectively connected with 45 the inner ends of the adjacently disposed levers 32. Thus it will be seen that when the lever 23 is rocked the links 25 and 26 will be reciprocated in opposite directions so that the levers 30 as well as the levers 32 will be rocked, but the last-mentioned levers will be rocked in opposite directions to the rocking of the levers 30 whereby the rods 35 to 40, inclusive, will be rocked in an opposite direction to the rocking of the rods 41 to 45, inclusive.

A series of sections of reflecting surfaces which may be mirrors or any other equivalent medium are rigidly connected to the outer projecting ends of the rods 24, 35 to 40, inclusive and 5 to 45, inclusive, and these sections of the reflecting surfaces are so constructed that they will form words, sentences, or figures or a combination of words and figures as an advertisement or display sign either within a building or exteriorly of said building. The reflecting surfaces, generally designated by the numeral 50, are so designed in Fig. 1 that they spell the word "Frocks" or any other word or group of words may be employed. It will also be noted in this instance that each word has sections 51 and 52 as shown in the letter "F" which are rocked by different shafts 24 and 35 but in this instance the two shafts are rocked in the same direction so that the reflecting members 51 and 52 are also rocked in the same direction. However, the members 53 and 54 forming the letter "r" are carried by the shafts 41 and 36 so that these reflecting members are rocked in opposite directions and this is also true of the remaining groups or pairs of reflecting surfaces. While only two pairs of shafts are illustrated in the drawings for rocking two sections of a letter it will be appreciated that any number of the sections may be employed to form a letter with each section being rocked by a different shaft and any combination of synchronous rocking or opposed rocking movement may be employed for the various reflecting surfaces forming a letter.

In order to produce a scintillating effect not only through the rocking of the mirrors synchronously in the same direction or in opposite directions the rear or backs of the reflecting surfaces are corrugated as shown in Figs. 5 to 8, inclusive, and these corrugations may be of different forms.

In Figs. 5 and 6 the vertical section of the reflecting surface gives the appearance of a saw having slanting sides 55 and substantially horizontal portions 56. The light striking these surfaces at different angles will cause the light rays to be projected at similar angles in different directions. Each of the surfaces, however, shown at 57, are covered with a reflecting medium of any well known type.

In Fig. 7 a modified form is shown in which the rear portion of the reflecting surfaces of the member 58 has concaved grooves 59 separated by upstanding ridges 60.

In Fig. 8 the member 61 is provided with convex surfaces 62 and spaced grooves 63. The entire rear surfaces in Figs. 7 and 8 are both covered with a reflecting medium of a well known type.

Located along one longitudinal edge of the housing 10 is a channel-shaped reflector 65 in which is placed an elongated lamp 66. This lamp may be of the well known filament type or it may be a neon lamp.

A plug 70 is adapted to be connected with the usual socket or house current and to this is connected a wire 71 running to the motor 13. Wires 72 and 73 extend from the plug 70 to a rheostat, generally designated by the numeral 14, while wires 75 and 76 extend from the rheostat to the neon lamp 66. The element 14 controls the voltage of the current through the lamp 66 and also to the motor 13 where the motor is of small capacity and the member 74 may be disregarded where the sign is of sufficient size that the house current

will operate the motor 13 and cause illumination of the lamp 66.

In Figure 9 is shown a modified form of the invention in which lamps 80 are oscillated or agitated together with reflectors 81 for projecting scintillating light rays on a sign as shown in Fig. 1 in which the letters are made up of fragmentary pieces of reflecting surfaces.

Each of the reflecting members 81 is carried by a head 82 which has a pintle 83 mounted in a block 84. The blocks 84 are carried by a base member 85.

The head 82, located at one extreme end of the base member 85, is connected to a yoke 87 formed on a reciprocating rod 88. This rod is reciprocated in any approved manner and more particularly in the manner shown in Fig. 2. The other series of levers 89 is pivotally connected at 90 with the rod 88 so that all of the reflectors 81 and the bulbs 80 are rocked in unison. On the other hand alternate arms 89 may extend in opposite directions and be reciprocated by a link as shown in Fig. 2 so that alternate lamps will project light rays in opposite directions and give approximately the same results as that obtained by the devices illustrated in Figs. 1 to 3, inclusive.

I claim:

1. A scintillating sign comprising a base, spaced rockable rods projecting upwardly from said base, a plurality of reflecting members secured to the free ends of the rods, a lever rigidly secured to each rod, alternate levers projecting in opposite directions, a link located upon each side of the group of rods and connected to the free ends of said levers, means oscillating said links for rocking the rods, and means projecting light rays on the reflecting members.

2. A scintillating sign comprising a base, spaced rockable rods projecting upwardly from said base, a plurality of reflecting members secured to the free ends of the rods, a lever rigidly secured to each rod, alternate levers projecting in opposite directions from the other levers, a link having pivotal connections with the free ends of the last-mentioned levers, a second link having pivotally connection with the free ends of the other levers, means for reciprocating the links alternately in opposite directions, and means projecting light rays on the reflecting members.

3. A scintillating sign comprising a base, a plurality of spaced rockable supporting means mounted on the base, a plurality of reflecting members arranged to form indicia and connected to the supporting means, means for rocking said supporting means, means projecting light rays on the reflecting members, and means included in the rocking means for causing alternate supporting means to be moved in an opposite direction to that of the other supporting means.

4. A scintillating sign comprising a base, a plurality of reflecting members arranged on said base to form indicia, means projecting light rays on said members, and means for rocking certain of the reflecting members in one direction while rocking the remaining reflecting members in the opposite direction.

5. A scintillating sign comprising a base, a plurality of reflecting members arranged to form indicia, means for projecting light rays on said members, means for moving the projecting means to cause the light rays to strike the reflecting members at various angles of incidence.

WALLACE G. McILVANIE.
